UNITED STATES PATENT OFFICE.

CHARLES A. WENDT, OF MILWAUKEE, WISCONSIN.

POOL-TABLE-POCKET IRON.

1,277,673.

Specification of Letters Patent. Patented Sept. 3, 1918.

Application filed March 11, 1918. Serial No. 221,716.

To all whom it may concern:

Be it known that I, CHARLES A. WENDT, a citizen of the United States, and resident of Milwaukee, in the county of Milwaukee and State of Wisconsin, have invented certain new and useful Improvements in Pool-Table-Pocket Irons; and I do hereby declare that the following is a full, clear, and exact description thereof.

10 This invention relates to improvements in game apparatus and more particularly to pool and billiard tables.

It is the object of my invention to provide an arrangement for connecting the pocket irons of a table of this character with the table rails in such manner that the irons may be removed and replaced from time to time without disturbing the securement of the rails to the table, and it is more particularly my object to provide for detachably securing the angle irons in such manner that the top surfaces of the meeting end portions of the rails are not disturbed in attachment or detachment of the irons.

25 An additional object is to provide a pocket iron of improved shape which will deflect the pool balls downwardly into the pocket of which it forms a part and thus obviate the possibility of the balls being projected over the pocket and off the table.

With these and other objects in view the invention consists in certain peculiarities of construction, combination and arrangement of parts which will be hereinafter more particularly described and claimed and shown in the drawings, wherein:

Figure 1 represents a plan view of one corner of a pool table showing my invention as applied to a corner pocket.

40 Fig. 2 is a similar view illustrating the relation of the invention to a side pocket.

Fig. 3 is an elevational view of a portion of a table with my invention associated therewith, and

45 Figs. 4 and 5 are vertical transverse sectional views taken on the planes of the lines 4-4 and 5-5 of Fig. 2.

In both forms of my invention similar reference characters indicate like parts, the numeral 1 being used to denote the usual slate bed or playing surface of a pool table, said surface being substantially rectangular and provided with retaining members to hold the usual balls thereon. These retaining

members comprise sills 2 and rails 3, the former being secured to the edges of the playing surface, while the latter are disposed on the top of said sills.

At predetermined points the table is provided with a plurality of pockets 4, such pockets each being formed by cutting an arcuate recess 5 in the playing surface and spacing the sills and rails adjacent such recess apart.

A pocket iron 6 is customarily employed to bridge the gap between the rails and to form a stop against which the balls directed into the pockets strike; the irons are also adapted to support one portion of the usual netting (not shown) forming the pocket proper. In the present invention the opposite end of the irons are flat and adapted to abut the adjacent ends of the rails 3 when the former are covered with the usual leather or the like.

Each of the irons is held in position by means of lugs 7, one of which projects from each end thereof, they being formed integrally with its bottom surface. Said lugs are readily removably disposed in longitudinally extending seats 8 formed in the sills 2 immediately beneath the rails 3. In other words the bottom of the rails form the tops of the recesses or seats 8, the inner ends of which open through the inner adjacent ends 85 of said sills. The outer sides of the seats are also open through the outer surface of the sills whereby to allow the lugs to be readily inserted thereinto or removed therefrom. In view of this construction it will be seen that 90 it is absolutely unnecessary to remove the rails 3 when any one of the pocket irons is to be detached from the table.

The several irons are held in position by bolts 9 that extend upwardly through the 95 sills 2 and openings in the lugs 7 as clearly shown in Fig. 5.

The inner surface of each pocket iron is inclined downwardly and outwardly at a sharp angle as at 10 in Fig. 4, and such surface is so disposed with respect to the playing surface 1 that a ball as it is projected into the pocket 4 will strike midway the inclined surface 10. In the present construction the balls are liable to strike the intersection of the inner and top surface of the iron and be deflected over the top of the latter and consequently off the table. My

improved iron will prevent such by directing the balls downwardly.

I claim:—

1. A game table of the class described including a playing surface, a pair of retaining members disposed at the edge of the playing surface and having their opposite ends spaced apart to receive a pocket therebetween, each of said members having a longitudinally extending seat opening through the end thereof, the outer side of said seat being also open through the outer surface of the retaining members, a pocket iron bridging the space between the adjacent ends of the retaining members and having its opposite ends abutting the same, a lug projecting from each end of the pocket iron, one of the lugs being positioned in each of said seats by disposing the same through the outer open sides thereof, and means engaging the lugs to retain the same in the seats.
2. A game table of the class described including a playing surface, a pair of sills

disposed at the edge of the playing surface and having their opposite ends spaced apart to receive a pocket therebetween, a rail disposed on each of said sills, the adjacent ends of said rails being spaced apart, each of said sills having a longitudinally extending seat opening through the end thereof, the top of said seats being formed by the bottom of said rails, the outer side of said seats being also open through the outer surface of the sills, a pocket iron bridging the space between the adjacent ends of the rails and having its opposite ends abutting the same, a lug projecting from each end of the pocket iron, one of the lugs being removably disposed in each of said seats, and means engaging the lugs to retain the same in said seats.

In testimony that I claim the foregoing I have hereunto set my hand at Milwaukee, in the county of Milwaukee, and State of Wisconsin.

CHARLES A. WENDT.
